CLAIM

The ornamental design for a container window design, as shown and described.

DESCRIPTION

FIG. 1 is a perspective view of a container window design, showing our new design;

FIG. 2 is front elevation view thereof;

FIG. 3 is a rear elevation view thereof;

FIG. 4 is a left side elevation view thereof; with the right side elevation being identical thereto; and,

FIG. 5 is a top plan view thereof; with the bottom plan view being identical thereto.

The broken line portion of the figure drawings is included to show unclaimed subject matter only and forms no part of the claimed design.
